LIFESAVING AND PROTECTING SUIT

Hans Georg Mörner, Stockholm, Sweden

Application March 28, 1940, Serial No. 326,337
In Sweden September 13, 1939

3 Claims. (Cl. 9—20)

The present invention relates to an improvement in life-saving and protecting suits of the kind which are provided with an entrance opening located, for instance, on the front side of the suit, for rendering it possible to put on and take off the suit, said opening being adapted to be closed by means of a locking and sealing device. The said sealing device consists, in a manner known per se, of strips of rubber or other elastic material which are attached to and extend along the two meeting edges of the said entrance opening, one of said strips being provided on the side facing the other strip with at least one longitudinally extending sealing groove, and the other strip being provided on the side facing the first-named strip with at least one corresponding longitudinally extending projecting sealing rib or tongue, the said rib and groove having such cross-sectional shapes that, due to the elasticity of the material, the rib may be forced in engagement with the corresponding groove by merely forcing the two strips against one another. In this way the sealing device may be easily and rapidly closed by the wearer himself, after he has put on the suit, for instance by means of a slide which is slidable along the two strips and which is provided with pressure members which act upon the outer sides of the strips and force the rib into the groove when the slide is moved along the strips. While the said sealing device is supposed to be water-tight and gas-tight, it cannot be quite relied upon to withstand such stresses which will arise when the suit is used, for instance while the wearer is swimming, and which tend to pull the rib out of engagement with the groove.

This is explained by the fact that, in order to render it possible easily and rapidly to close the sealing device, the rib and the groove must have such cross-sectional shapes that the rib can be brought in engagement with the groove merely by exerting a slight pressure on the two strips to force the same against one another, and there is, therefore, a great risk of the rib being wholly or partially pulled out of the groove due to the abovementioned stresses which arise when the suit is being used.

The primary object of the present invention is to obviate this difficulty. For this purpose the invention consists principally in the opening being provided, in addition to the sealing device formed by the two abovementioned strips, also with a sliding fastener, a so-called lightning fastener, the locking members of which are attached to the meeting edges of the opening under the strips. By this arrangement the said sliding fastener will

take up such stresses that might otherwise pull the rib out of engagement with the groove, so that security is obtained for the sealing device remaining water-tight and gas-tight. The sliding fastener provided under the strips also provides the great advantage that by the closure of the said fastener the two elastic strips are brought in the correct position opposite one another, so that the sealing device formed by the said two strips can easily and rapidly be securely closed by the wearer himself.

In order to render the sealing device absolutely tight it is suitable to provide one of the elastic strips with a comparatively thin flange or lip which is so placed that, when the rib has been brought in engagement with the corresponding groove, the said lip will come to bear against the outside of the other strip, so that when the suit is used in water, the lip is forced against the last-mentioned strip by the pressure of the water.

A constructional form of the invention is illustrated by way of example in the accompanying drawings. Figs. 1 and 2 show a life-saving suit according to the invention, Fig. 1 showing the sealing device fully closed, and Fig. 2 showing the same partially closed. Fig. 3 shows to a larger scale a portion of the sealing device viewed from the front, and Fig. 4 shows a section through the sealing device on the line IV—IV in Fig. 3. Fig. 5 shows a detail of the sealing device.

The suit illustrated in the drawings consists of a jacket portion 1 which is intended to surround the body of the wearer, sleeves 2 with gloves 3, trousers 4, and an elastic collar 5 which is intended to closely surround the neck of the wearer. All these parts are made in one integral piece of rubber fabric or some similar water-tight and gas-tight fabric. The jacket 1 is provided on the inside, and preferably both at the front and at the back side, with paddings 6 which may suitably be filled with kapok or some similar material which gives the suit a good buoyancy in water.

The suit is provided with a single entrance opening 7 which, in the instance illustrated, is placed at the front side of the suit and which extends from the upper edge of the collar 5 down to the point where the jacket joins the trousers, so as to make it possible to put on the suit rapidly.

When the suit has been put on, the opening 7 must be closed in a water-tight and gas-tight manner. For this purpose the opening is provided with a sealing device which consists of two strips 8 and 9 of rubber or similar elastic mate-

rial, which strips extend along the two meeting edges of the opening and are attached to said edges by means of flexible flanges or bands 10 and 11, respectively, for instance in the manner that will be apparent from Fig. 4. The strip 8 is provided on the side facing the strip 9 with a groove 12 and with a projecting rib 13, and the strip 9 is provided on the side facing the strip 8 with a projecting rib 14 which is adapted to be brought in engagement with the groove 12, and with a groove 15 which is adapted to receive the projecting rib 13 on the strip 8. These strips and grooves have such cross-sectional shapes that, as shown in Fig. 4, the greatest width or thickness of the ribs is somewhat larger than the width of the openings of the grooves, so that when the two strips are forced against one another it is only due to the elasticity of the material that the ribs 13 and 14 can be brought in engagement with the opposing grooves 15 and 12, respectively.

In the constructional form illustrated, the strip 9 is provided with a comparatively thin flange or lip 16 which will lie against the outer side of the strip 8 when the ribs have been brought in engagement with the grooves, and when the suit is used in water, the said lip will be forced by the pressure of the water against the said strip. In this way it is fully ensured that the sealing device becomes completely water-tight and gas-tight.

In order to render possible a rapid closure of the sealing device there is provided a slide 17 which is slideable along the two strips 8 and 9 and which, in the constructional form illustrated, is provided with two pairs of rollers 18 and 19 which are journalled on pins and which engage longitudinal grooves 20 in the outer sides of the strips. The distance between the two rollers of each pair is such that when the slide is moved along the strips the rollers force the strips against each other and thus force the ribs 13 and 14 in engagement with the corresponding grooves 15 and 12, respectively. In order to facilitate the said sliding movement of the slide 17 the latter is provided with a yoke 21 which is pivotally attached to the slide and which serves as a handle. In order to secure the engagement thus produced between the ribs and the grooves of the strips there may be provided on the strips, if desired, one or more additional and somewhat simpler slides of the type illustrated in Fig. 5 and at the bottom of Fig. 3.

These slides consist simply of a metal strip 22 bent to U-shape, and the bent ends 23 of the shanks of which engage the grooves 20 in the strips 8 and 9. Also these slides 22 may be provided with yokes 24 serving as handles, if it is desired to displace and adjust each slide separately. This is not necessary, however, as the slides 22 may also be connected to one another and to the main slide 17 by means of flexible pull members 25, for instance chains or metal bands, in such manner that when the main slide 17 is pulled upwards, the other slides 22 are brought along, each one in its turn, and are thus automatically adjusted at the desired distances from one another, which distances are defined by the length of the pull members. The lowermost slide 22 shown in Figs. 1 and 2 is supposed to be attached to the lower ends of the strips and thus serves together with the said pull members 25 to limit the upward movement of the other slides.

In order to securely prevent the ribs 13 and 14 from being pulled out of engagement with

the grooves 15 and 12 due to stresses which may arise when the suit is used, for instance, when the wearer is swimming, and which tends to pull the strips apart, the opening 7 is provided, according to the invention, in addition to the above-mentioned sealing device consisting of the two strips 8 and 9, also with a sliding fastener. This fastener is suitably of the kind which consists of locking members 26 which are attached to the edges of the opening under the strips 8 and 9, and which may be brought in and out of engagement with one another by the displacement of a locking slide 27 to which a string 28 serving as a handle is attached.

When the suit is not used both the sliding fastener and the sealing device 8, 9 should of course be fully open to render it possible to put on the suit rapidly. The slides 17 and 22 as well as the locking slide 27 of the sliding fastener should then be pushed down to the lower end of the opening 7. Due to the great length of the opening 7 the suit may then be easily put on without the aid of other persons. It is suitable first to put on the trousers 4, and afterwards the sleeves 2 and 25 the gloves 3, and finally the jacket 1. The wearer then takes hold of the string 28 and pulls the locking slide 27 of the sliding fastener all the way up to the upper edge of the collar 5 to which the sliding fastener extends. At the same time the two strips 8 and 9 are brought in the correct position opposite one another. The wearer now takes hold of the handle 21 of the slide 17 and pulls said slide up to the upper end of the strips 8 and 9, where the movement of the slide may be limited by a suitable stop, if desired. As shown in Fig. 2, the strips 8 and 9 may suitably end at the lower edge of the collar 5, with a view not to render the collar too stiff and inconvenient to the wearer, and to render it possible to open the collar for airing the suit when the wearer is in the water. The additional slides 22, if used, may then be pulled upwards and adjusted at suitable distances from one another, as indicated in Fig. 1. Again, if the said slides 22 are connected to one another and to the slide 17 by means of flexible pull members 25 in the manner above explained, the slides 22, with the exception of the lowermost one, will move upwards when the slide 17 is pulled up.

50 The wearer can now safely jump into the water, where he will be kept floating by the air enclosed in the suit and by the paddings 6. Simultaneously, the air enclosed in the suit is heat-insulating, so that even if the wearer has to stay in the water for a long time, his health will not necessarily be impaired.

60 The constructional form above described and illustrated in the drawings is only to be regarded as an example, and it will be understood that its details may be modified in various ways without departing from the principle of the invention. If the suit is to be used as a protecting suit against gas attacks, it should of course be combined with a gas-tight cap of rubber fabric or the like and with a gas mask.

65 I claim:

1. A life-saving suit having a collar and an entrance opening dividing said collar and extending downwards therefrom, a sealing device for 70 said opening extending upwardly from the lower end of said opening to the lower edge of said collar and comprising sealing strips of elastic material adjacent the meeting edges of said opening, one of said sealing strips having at least one groove extending longitudinally thereof, and the

other of said sealing strips having at least one projecting rib to substantially fit the same and extending longitudinally thereof, the said rib and groove being of such cross-sectional form that said groove may be forced onto said rib in sealing engagement therewith due only to the elasticity of the material thereof, a slide holding the adjacent portions of said strips in sealing engagement and slidably thereon to complete the closing of said sealing device, and a sliding fastener comprising a slide and two interfitting and intermeshing members each attached to one of the meeting edges of said entrance opening inside of said sealing device and extending from the lower end of said entrance opening to the upper edge of said collar, whereby said sealing device covers said sliding fastener except at the upper end thereof, to permit said collar to be closed initially but opened subsequently without opening said sealing device.

2. In a life saving suit or the like, an entrance opening, a sealing device for said opening comprising sealing strips of elastic material along the meeting edges of said opening, one of said sealing strips having at least one groove extending longitudinally thereof, and the other of said sealing strips having at least one corresponding projecting rib extending longitudinally thereof, the said rib and groove being of such cross-sectional form that said groove may be forced onto said rib in sealing and locking engagement therewith due only to the elasticity of the material thereof, at

least one of said sealing strips having a thin flexible flange which extends over a substantial part of the adjacent surface of the other sealing strip when said sealing strips are in sealing and interlocking engagement, said flange bearing closely against and overlying the outer surface of said other sealing strip so as to provide additional sealing action for the interlocked joint when said engaged strips are subjected to external pressure.

3. In a life saving suit or the like, an entrance opening, a sealing device for said opening comprising sealing strips of elastic material along the meeting edges of said opening, one of said sealing strips having at least one groove extending longitudinally thereof, and the other of said sealing strips having at least one corresponding projecting rib extending longitudinally thereof, the said rib and groove being of such cross-sectional form that said groove may be forced onto said rib in sealing and locking engagement therewith due only to the elasticity of the material thereof, each of said sealing strips having a thin flexible flange which extends over a substantial part of the adjacent surface of the other sealing strip when said sealing strips are in sealing and interlocking engagement, said flanges bearing closely against and overlying the adjacent surface of said other sealing strip so as to provide additional sealing action for the interlocked joint when said engaged strips are subjected to fluid pressure.

HANS GEORG MÖRNER.
